UNITED STATES PATENT OFFICE.

MILON J. TRUMBLE, OF ALHAMBRA, CALIFORNIA.

HYDROGENATING AND CRACKING ORGANIZATION.

Application filed December 24, 1924, Serial No. 757,809. Renewed November 12, 1928.

Although my present invention is referred to as a hydrogenating and cracking organization, this invention includes not only a cracking apparatus comprising a hydrogenator or hydrogenators and an equilibrium chamber, but also a method or methods in which said apparatus may be employed; and it is a primary object of this method to provide light hydrocarbon oil mixtures comparatively free from unsaturated compounds.

It is a further object of this invention to provide economical and efficient means for producing relatively large quantities of comparatively light hydrocarbons, such as hydrocarbon mixtures marketable as gasoline, from heavier hydrocarbon oils; and a preferred embodiment of my invention may comprise a substantially horizontal two-compartment equilibrium chamber functionally interposed between a plurality of hydrogenators.

One or more of my hydrogenators may be heated, or the contents thereof may be heated, wholly or in part, by steam, or by another heated hydrogenating agent, or by a mixture of such agents; and such agents are preferably brought to a cracking or reacting temperature within a dome or other interior part of a hydrogenator. Hydrogen may be produced within this dome.

It is a further object of this invention to provide an oil treating system comprising a primary hydrogenator and a secondary or finishing hydrogenator so related that what I term my finishing hydrogenator, which may serve also for the separation of heavy vapors, shall contribute incidentally to the preheating of new oil on its way to my primary hydrogenator, and, in a preferred embodiment of my invention, this primary hydrogenator may comprise or be associated with the mentioned dome or part provided with, for example, an electrical resistance heater, or the like, adapted to elevate steam or any preferred hydrogenating mixture to a temperature favorable to the desired cracking and hydrogenating effects, and exempt, by reason of its position, from damage due to heat and pressure.

It is a further object of my invention to provide a cracking and hydrogenating organization comprising a high temperature primary hydrogenator to which oils are returned during the continuous delivery of a cracking and hydrogenating agent thereto; and, in this preferred embodiment, this hydrogenator, whether or not the same is provided with a dome in which steam or the like is electrically preheated, may comprise a substantially horizontal plate provided with perforations through which oil to be cracked or hydrogenated is blown or forced as a rain or mist; and into this rain or mist, which may contain a carbonaceous residue resulting from a previous passage of oil through the same or another apparatus or a part thereof, I may admit any desired proportion of new oil preheated in the manner referred to or in any preferred way, the new oil so introduced being preferably delivered upwardly into such rain of returned oil admixed with a hydrogenating agent or agents suitably heated.

It is a further object of my invention to provide means permitting steam, or the like, used as a hydrogenating agent, to be admixed in any desired proportions with an acid or a catalytic or other chemical agent, this admixture preferably occurring in advance of the entrance of the steam, or its equivalent, into my described primary hydrogenator; and, independently of or in conjunction with the reagent admixing means last referred to, which may comprise one or more chemical tanks connected with a steam main and each having a plurality of valved connections therewith, I may optionally employ means permitting either automatic or manual manipulation of additional valves predetermining and maintaining a desired minimum pressure of steam, or the like, throughout my organization, or throughout a portion thereof.

It is a further object of my invention to provide a hydrogenating cracking organization in which both a primary or cracking hydrogenator and a secondary or separating hydrogenator, which may or may not closely resemble those above mentioned, are structurally associated with a novel and preferably horizontal equilibrium chamber; and, in a preferred embodiment, this equilibrium chamber may comprise two compartments extending longitudinally thereof; and one or both of said compartments may contain a scraper or conveyor; and means may be provided, as by direct application of bottom heat to one of said compartments, for maintaining the temperature of a mixture

110

therein during an interval of time in which reactions initiated in a hydrogenator may continue and in which volatile constituents, and sediments, may be separated therefrom.

5 It is a further object of this invention to provide a novel two-compartment equilibrium chamber in which communicating passages to and from said compartments are so arranged as to assure preservation of a vapor 10 space in each of the same and one of said vapor spaces may advantageously be in open or direct communication with each of my mentioned hydrogenators or their equivalents.

15 It is a further object of this invention to provide a cracking and hydrogenating organization of the general character referred to, with means whereby sedimentary materials formed or accumulated in one of the 20 mentioned compartments, such as a lower compartment, whose temperature may be maintained by a fire, therebelow, may be pumped or otherwise forced back, together with uncracked or partially cracked or partially hydrogenated oils, into my primary 25 hydrogenator, or its equivalent, vapors from this compartment being preferably permitted simultaneously to advance from said chamber into my secondary or separating hydrogenator, or its equivalent.

It is a further object of my invention to provide a cracking and hydrogenating organization of the general character referred to in which one or more of the mentioned 35 scrapers or conveyors, if provided in the mentioned compartments or their equivalents, may be adapted to eliminate a carbonaceous residue or sediment into a carbon pot or pots; and, in a preferred embodiment, 40 this scraper or conveyor may advance said residue in a direction opposite to the movement of a mixture of oil, vapors and gas, through said compartments; and means may also optionally be provided, whereby superheated steam may be employed to return 45 any recoverable oils or oil vapors from said carbon pots to said hydrogenator.

Other objects and advantages of my invention, including the provision of means 50 whereby any heavy oils accumulating in my secondary or separating hydrogenator may be returned therefrom, and including also means whereby a scraper may be tensioned, will appear from the following description 55 of an illustrative embodiment thereof, taken in connection with the appended claims and the accompanying drawings, in which

Fig. 1 is a diagrammatic vertical section through an organization suitable for use in 60 the practice of my invention.

Fig. 2 is a vertical section taken substantially as indicated by the line 2-2 of Fig. 1, with parts omitted or broken, and with heat insulation omitted.

65 Fig. 3 is a vertical section taken substan-

ti ally as indicated by the line 3-3 of Fig. 1, with parts omitted or broken, and with heat insulation omitted.

Fig. 4 is a slightly enlarged horizontal sectional detail view taken substantially as indicated by the line 4-4 of Fig. 1.

Referring to the details of that specific embodiment of my invention chosen for purposes of illustration, 11 may be a substantially horizontal equilibrium chamber used 75 to support, and functionally interposed between, a primary or separating hydrogenator 12 and a secondary hydrogenator 13, the mentioned primary hydrogenator being shown as provided with a pipe 14 for the 80 admission of steam, or the like, into a dome 15, shown as constituting the upper part thereof and as containing an electrical resistance heater 16, shown as grounded at one end and as connected at its other end 85 with a feed wire 17, passing through an insulator or insulators 18. Any desired number or sleeves 18' may surround this heater, to reduce heat losses.

Instead of admitting the oil to be treated 90 directly into the primary hydrogenating chamber 12 or the dome 15, I consider it advantageous to provide a jacket 19 about the secondary hydrogenator 13, or about another portion of my apparatus, and to 95 admit new oil by means such as an inlet pipe 20, shown as extending from a pre-heater 21 to a point near the bottom of said jacket, a valved pipe 22, or its equivalent, extending from a point near the top of said 100 jacket being employed to conduct oil pre-heated thereinto into the interior of the primary hydrogenator 12, in which it may be provided with an upwardly extending terminal portion 23.

Between the dome 15 and the terminal portion 23, constituting an oil delivery inlet, or at another suitable level within the primary hydrogenator 12, or its equivalent, I may provide a perforated plate 24 or its 110 equivalent, adapted to subdivide, into what I may term a mist or rain, any material advanced thereto; and any mixture comprising a mineral oil and a preheated hydrogenating agent descending through the primary 115 hydrogenator may pass therefrom directly into my equilibrium chamber 11. This equilibrium chamber may be of any preferred character, but I have shown the same as comprising a single external shell substantially circular in cross-sectional outline, and as divided by a partition 25 into an upper compartment 26 and a lower compartment 27, the upper regions of these compartments being shown as connected near one end thereof by a pipe 28 and each of said compartments being provided with a separate conveyor or scraper.

My equilibrium chamber being designed 120 to permit an advance of the reactions ini-

125 130

ated in the primary hydrogenator 12, or its equivalent, and a separation of sediments and of volatile fractions, I may provide, at or near what I may term the inner end 5 of the lower compartment 27, an opening 29 communicating, as by means of an inclined pipe 30, with the interior of the secondary hydrogenator 13, or its equivalent; and one of the mentioned scrapers or conveyor, as 10 the conveyor 31 provided in the upper compartment 26 of my equilibrium chamber, may be adapted to deliver a carbonaceous residue, as by means of a valved passage or passages 32, into a carbon pot or pots 33. 15 One of these pots may be used at a time, and means such as valved steam pipes 34 may be employed to return any residual oils therefrom, as by way of a valved pipe or pipes 35, to, for example, the primary hydrogenator 20 12.

The levels of openings 36 and 37, at the respective ends of the pipe 28, or its equivalent, and the level of the opening 29 by which one compartment of my equilibrium 25 chamber is in constant communication with the secondary hydrogenator 13, may be such as to assure the preservation of a vapor space in the tops of the respective compartments 26 and 27; and means such as a direct 30 application of fire, as by means of a furnace 38 therebelow, may be employed to maintain the temperature of the oil mixtures advancing in opposite directions through said compartments at such a level as to expedite the 35 attainment of equilibrium and the production of a maximum quantity of desired saturated compounds therein. When I use direct heating means such as are above suggested for maintaining the temperature of my equilibrium 40 chamber, a gas or oil flame, or the like, may be projected through an opening 39, or shale stripped of its hydrocarbons may be delivered therethrough, and products of combustion may escape through, for example, 45 a flue 40, leading to a stack, or the like, not shown.

It will be obvious that my equilibrium chamber, or its equivalent, may be given any desired length favorable to the attainment 50 of its functions; and that it may be subdivided into any required number of compartments; and also that the conveyors or scrapers employed therein may be of any usual or preferred character; but I show the 55 spiral conveyor 31 of the upper compartment 26 as provided with a drive pulley 41, and as adapted to advance sediments in a direction opposite to the movement of fluids therethrough; and I show in the lower compartment 60 27 a chain conveyor or scraper 42, adapted to deliver to a pump 43, or its equivalent, driven by a pulley 44, a mixture of oils containing any carbonaceous residues formed or settling in said compartment, and 65 the outlet of this pump may communicate

with, for example, my primary hydrogenator 12, as by a pipe 45, shown as provided near its upper end with an expansion 46, terminating just above the plate 24, in such manner as to return heavy uncracked or unsaturated 70 oils and residues, at low velocity, to a position wherefrom they may be rained or blown through said plate, or its equivalent, in intimate contact with a new quantity of a hydrogenating agent or agents; and this recirculation, including a withdrawal of sediments from compartment 26 and an escape of vapors from compartment 27 into the secondary or finishing hydrogenator 13 may be repeated as often as desired, with or without 80 a continuous admission of preheated or other new oil by the means described, or their equivalents.

When I employ a chain conveyor serving as a scraper in the compartment 27, this 85 being an advantageous construction in case bottom heat is employed, I may support the chain 42, carrying blades 47, from suitable pairs of sprocket wheels 48 and 49, these sprockets being shown as mounted upon 90 shafts 50, 51, one of which is provided with bearings 52, which may be supported from the curved walls of the lower compartment 27; and, in order to facilitate the tensioning of the chain 42, and to compensate for wear 95 of parts, I may optionally support one of said shafts, as the shaft 50, upon horizontal shelves or ledges 53, 53', (Fig. 4) and I may provide bearings 52' in a yoke 54, integrally or otherwise rigidly connected with a sliding 100 rod 55. This rod is shown as extending through a gland 56 in one end of the chamber 27, and as provided with adjustable tensioning means in the form of a nut 57 engaging threads on said rod and adapted to contact with a bracket 58, extending forwardly from said end of the chamber 27; but it will be understood that the construction last referred to is merely an optional detail, designed to overcome the difficulties incidental 110 to the operation of a scraper or conveyor in a chamber containing fluids under pressure.

A predetermined pressure, such as a pressure of 150-200 pounds, more or less, may be maintained throughout the described organization, or throughout any predetermined portions thereof, by any suitable means, such as the provision of an automatic valve at 59 in the pipe 14, by which steam at a suitable temperature, such as a temperature of 800° 115 to 1000° F. may be introduced into the primary hydrogenator 12, or into the dome 15, shown as positioned thereabove, the automatic valve 59 being shown as provided with a diaphragm chamber 60, from which a branch 61 extends to the pipe 14, in which a hand valve 62 may also be provided; and in order to facilitate the introduction of hydrochloric acid, or sulfuric acid, or any other desired catalytic or chemical agent, 125 130

into the primary hydrogenator 12, or its equivalent, I may optionally provide means such as the tanks marked H_2SO_4 and HCL, these tanks being respectively provided with 5 valves 63 and 64 in pipes 65 and 66, leading respectively to the pipe 14, and a valved pipe 67 being shown as connecting the tops of these respective tanks with the steam pipe 14, in such manner as to permit an equilization 10 of pressure therein.

By the means described, or equivalent means, it will be obvious that steam may be admixed with a desired reagent in advance of its admission into the dome 15, or its 15 equivalent, and it may therein be economically and safely heated to any desired temperature, as a temperature of 1600-2000° F, or to a temperature producing any desired thermal decomposition, after which it 20 may pass downward into an intermediate region 68 of the primary hydrogenator 12, serving therein to force such oil as may be returned through the pipe 46, or its equivalent, in the form of a rain or mist, through 25 apertures 69 in the plate 24; and this rain or mist, constituting an intimate mixture of oils and hydrogenating agents at a high temperature, may encounter new oil, pre-heated in the jacket 19 of the secondary 30 hydrogenator 13 and delivered upwardly from which carbon residues are withdrawn 35 as described, and to pass therefrom through the connecting pipe 28 into the compartment 27, a vapor space being maintained in both of said compartments and vapors being permitted to flow out from the latter compartment 40 through the opening 29 and the pipe 30 into the secondary hydrogenator 13, whereas heavier oils and residual carbon are returned by the pump 43 and the pipe 45 for retreatment as described, the desired temperature being maintained by any suitable means throughout the equilibrium chamber, and any recoverable hydrocarbons being blown back from the carbon pots 33 50 into the region 68, or into any preferred region of the organization described. The nature and position of the heater 18 assures its safety and also its protection from carbon incrustations, or the like.

55 Oils obtained from shale or from any other suitable source may be treated in my present apparatus. It will be understood that hydrogenating reactions initiated in the primary hydrogenator 12, or its equivalent, whether or not these include a production of H_2 by a thermal decomposition, are intended to continue throughout the period during which the resultant mixtures are retained in the equilibrium chamber 11, 60 through both or all compartments of which

the said admixtures are forced to travel before vapors evolved therefrom are permitted to escape from the opening 29; and the vapors so escaping, which may contain light hydrocarbons admixed with steam, with or without added reagents, a certain proportion of fixed gases and relatively heavy hydrocarbons being unavoidably advanced therewith, may pass into the lower portion of the hydrogenator 13, or its equivalent.

This hydrogenator 13 is preferably so designed as to favor a continuance of hydrogenating reactions therein. For example, the pipe 30, entering laterally into the lower portion of said hydrogenator may terminate upwardly, as at 70, beneath a baffle 71, shown as resembling an inverted cup; and a series of any desired number of such bafflers may be provided, one above another, and optionally supplemented by means such as plates 72, shown as centrally apertured and as integral with downward tubular extensions 73. Baffles 71 and plates 72, or their equivalents, may be supported by brackets (not shown), the arrangement here referred to being such

that vapors passing from the outlet 70 of the pipe 30 must pass downwardly and outwardly about the inverted cup 71 into a space 74 surrounding a tubular extension 73, then centrally toward such an extension, and up therethrough into a space 75 within another inverted cup, continuing thus toward a final outlet, such as the outlet 76 about the top of the hydrogenator 13. This hydrogenator serves as a finishing or separating hydrogenator in the bottom 77 of which comparatively heavy oils, imperfectly cracked or incompletely hydrogenated, may collect. These heavier oils or fractions may be returned to the equilibrium chamber or to the primary hydrogenator 12, as by means of a valved pipe 78, shown as terminating in the bottom of said hydrogenator, the valve in this pipe being either automatic or manual, as shown; and the vapors, including the desired gasoline fraction, escaping through the outlet 76 may pass through the mentioned preheater 21, exchanging heat in the indicated manner with quantities of new oil admitted therethrough, past a valve 79 and into any receptacle or fractionating organization (not shown) suitable for the separation and purification of the desired products.

As suggested in the drawings, the described preheating and hydrogenating and equilibrium chambers, and the connections therebetween, may advantageously be insulated in such manner as to minimize the radiation of heat therefrom; and it will be understood that, although I may find it advantageous to provide for a practically continuous admission of oil past the valve 80 in the pipe 81, by which new oil is admitted to the preheater 21 and advantageous also to permit a practically continuous inflow of

steam past the valve 62 in the pipe 14, the escape of desired vapors past the valve 79 in the vapor outlet being then presumably continuous, the operation of either or both 5 of the scrapers or conveyors described may be intermittent; and the carbon pots 33 are preferably to be used alternately, carbon residues being received by one during the time when steam is being blown through the other 10 and the contents thereof are being withdrawn; but the preferred mode of operation of the entire organization, or any part thereof, may be intermittent or otherwise widely different from that above described; and, in 15 the treatment of some materials, all application of external heat may be dispensed with.

Although I have herein described a preferred form of my invention, I am aware that various changes and modifications may 20 be made by those skilled in the art to which this case relates, without the slightest departure from the spirit and scope of my invention, as the same is indicated above and in the following claims; and I may especially emphasize the fact that for the purpose 25 of generating electrical or other power, I may optionally interpose a turbine generator, or the like, in the outlet pipe 76, or its equivalent, in which it may, for example, 30 replace the valve 79.

I claim as my invention:

1. In an apparatus of the character described, an equilibrium chamber provided with an outlet for lighter fractions, a hydrogenator disposed above and delivering directly thereto, and means independent of means for supplying new materials for repeatedly passing heavier fractions back from said chamber through both said hydrogenator and said chamber.

2. An apparatus as defined in claim 1 in which said chamber comprises a plurality of directly superimposed and serially connected compartments, and scraping means in one 45 of said compartments for the removal of carbonaceous residues.

3. An apparatus as defined in claim 1 in which said chamber comprises a plurality of directly superimposed and serially connected compartments, and scraping means in one of said compartments for the removal of carbonaceous residues, and in which one of said compartments is provided with temperature maintaining means.

55 4. An apparatus as defined in claim 1 in which said chamber comprises a plurality of directly superimposed and serially connected compartments, whereby a mixture containing oils and sediments is forced back 60 into said hydrogenator and from one of which vapors are conducted to another hydrogenator.

5. An apparatus as defined in claim 1 in which said chamber comprises a plurality

of directly superimposed and serially connected compartments, one of said compartments being provided with an outlet for sediment and another of said compartments being provided with an outlet for vapors.

6. An apparatus as defined in claim 1 in which said chamber comprises a plurality of compartments, one of said compartments being provided with an outlet for sediment and another of said compartments being provided with an outlet for vapors, and a finishing or separating hydrogenator being connected with said last mentioned outlet.

7. In an apparatus of the character described, an equilibrium chamber comprising: a single external shell, an upper compartment and a lower compartment separated by a longitudinal partition in the form of a trough; conveyors in said compartments adapted to advance carbonaceous sediments in parallel directions; and means for maintaining the temperature of a mixture therein, one of said compartments being provided with a chain conveyor and the other with a spiral conveyor, and each being provided with an outlet in the upper part thereof.

8. In an apparatus of the character described, an equilibrium chamber comprising: a single external shell, an upper compartment and a lower compartment separated by a longitudinal partition in the form of a trough; conveyors in said compartments adapted to advance carbonaceous sediments in parallel directions; and means for maintaining the temperature of a mixture therein, said compartments being in constant communication by a pipe opening at such a level as to permit the passage of fluids while substantially preventing the passage of residual solids from the upper compartment 105 to the lower compartment.

9. In an apparatus of the character described, a substantially horizontal chamber comprising a cylindrical shell subdivided by a V-shaped partition, a plurality of separate hydrogenators extending upward from said equilibrium chamber, means for admitting oil into and through one of said hydrogenators, and means for withdrawing vapors through the other of said hydrogenators.

10. In an organization as defined in claim 9, means in said last mentioned hydrogenator for the separation of heavier fractions from lighter fractions passing therethrough.

11. In an organization as defined in claim 9, means in said last mentioned hydrogenator for the separation of heavier fractions from lighter fractions passing therethrough, and means surrounding said last mentioned hydrogenator for preheating the oil so admitted.

12. An organization as defined in claim 9, in which said partition forms two compart-

ments each having a vapor space, and open means of communication between said vapor spaces and said respective hydrogenators.

13. In an organization as defined in claim 5 9, means for effecting a heat exchange between vapors led from said last mentioned hydrogenator and said oil advancing toward said chamber.

14. In an organization as defined in claim 10 9, means for returning a heavier hydrocarbon mixture from said chamber to one of said hydrogenators.

15. In an organization as defined in claim 15 9, means for returning a heavier hydrocarbon mixture from said chamber to one of said hydrogenators, and means for producing therein a rain of said mixture in intimate contact with a hydrogenating agent.

16. In an organization as defined in claim 20 9, means for returning a heavier hydrocarbon mixture from said chamber to one of said hydrogenators, means for producing therein a rain of said mixture in intimate contact with a hydrogenating agent; and 25 means for introducing preheated new oil into said rain.

17. In an organization of the character described, an equilibrium chamber, a primary hydrogenator containing a perforated 30 partition, a separating hydrogenator, and means whereby oils are fed through a jacket about the separating hydrogenator into the interior of said primary hydrogenator, and therefrom into said chamber, and from said 35 chamber in part back above said partition.

18. An organization as defined in claim 17 in which a valved passage is provided between the bottoms of said hydrogenators.

19. An organization as defined in claim 40 17, in which said chamber is divided into two compartments, one of which is provided with a vapor outlet leading to said separating hydrogenator.

20. An organization as defined in claim 45 17, in which said chamber is divided into two compartments, one of which is provided with a vapor outlet leading to said separating hydrogenator, and with means for maintaining the temperature thereof.

21. An organization as defined in claim 50 17, in which said chamber is divided into two compartments, one of which is provided with a vapor outlet leading to said separating hydrogenator, with means for maintaining the temperature thereof, and with means for advancing sediment accumulating on its wall toward an outlet.

22. An organization as defined in claim 60 17, in which said chamber is divided into two compartments, one of which is provided with a vapor outlet leading to said separating hydrogenator, with means for maintaining the temperature thereof, and with means for advancing sediment accumulating on its wall toward an outlet provided

with a pump for returning a mixture containing the same toward said primary hydrogenating chamber.

23. An organization as defined in claim 17, in which said chamber is divided into two 70 compartments, each provided with means for the removal of sediment, means being provided for returning the sediment from one of said compartments to a hydrogenator.

24. An organization as defined in claim 17, 75 in which said chamber is divided into two compartments, each provided with means for the removal of sediment, means being provided for blowing steam through a carbon pot into which a carbonaceous sediment 80 is delivered.

25. An organization as defined in claim 17, in which said chamber is divided into two compartments, each provided with means for the removal of sediment, means 85 being provided for blowing steam through a carbon pot into which a carbonaceous sediment is delivered and for passing the resultant steam mixture into one of said hydrogenators. 90

26. An organization for the purpose set forth which comprises: a hydrogenator disposed directly above a substantially horizontal equilibrium chamber and into part of which steam is admitted, and internal means 95 in said part for superheating said steam after its admission; and in which said hydrogenator comprises a steam dome, the heating means therefor being an electric heater below which is disposed a perforated partition 100 through which oil and steam are forced as an intimate mixture at an elevated temperature.

27. An organization for the purpose set forth which comprises: a hydrogenator disposed directly above a substantially horizontal equilibrium chamber and into part of which steam is admitted, and internal means in said part for superheating said steam after its admission; and in which said hydrogenator comprises a steam dome, the heating means therefor being an electric heater above a perforated partition through which oil and steam are forced as an intimate mixture at an elevated temperature, 115 and has an inlet pipe positioned to deliver new oil into said mixture.

28. An organization for the purpose set forth which comprises: a hydrogenator disposed directly above a substantially horizontal equilibrium chamber and into part of which steam is admitted, and internal means in said part for superheating said steam after its admission; and in which said hydrogenator is connected with a second hydrogenator by a valved passage near the bottom thereof, said hydrogenators being both mounted on said equilibrium chamber. 120 125

29. An organization for the purpose set forth which comprises: a hydrogenator dis- 130

posed directly above a substantially horizontal equilibrium chamber and into part of which steam is admitted, and internal means in said part for superheating said steam after its admission; and in which said hydrogenator is connected with a second hydrogenator by a valved passage, near the bottom thereof, terminating in an outlet from said first mentioned hydrogenator, said hydrogenators 10 being both mounted on said equilibrium chamber.

30. In an apparatus of the character described, a two-compartment equilibrium chamber, a chain conveyor in one of the compartments thereof; and means extending to the exterior of said chamber through an end thereof for adjusting the tension of said conveyor.

31. In an apparatus of the character described, an equilibrium chamber, a hydrogenator in open communication with said equilibrium chamber, means for introducing superheated steam into said hydrogenator, means for separately introducing raw oil 20 into said hydrogenator, means for delivering residual oils from said equilibrium chamber into said hydrogenator, a secondary hydrogenator, means for delivering vapors from said equilibrium chamber to said secondary hydrogenator, means for withdrawing vapors from said secondary hydrogenator, means for returning residual oil from said secondary hydrogenator to said equilibrium chamber, and means for removing carbonaceous residue from said equilibrium chamber.

32. In an apparatus for the character described, an equilibrium chamber, a hydrogenator in open communication with said equilibrium chamber, means for introducing superheated steam into said hydrogenator, means for separately introducing raw oil 40 into said hydrogenator, means for delivering residual oils from said equilibrium chamber into said hydrogenator, means for withdrawing vapors from said equilibrium chamber and means for removing carbonaceous residue from said equilibrium chamber.

33. In an apparatus of the character described, an equilibrium chamber provided with an outlet for lighter fractions, a hydrogenator in open communication with said equilibrium chamber, means for introducing a hydrogenating agent into said hydrogena-

tor, means for repeatedly passing back from 55 said equilibrium chamber into said hydrogenator heavy fractions; means in said hydrogenator for intimately mixing and forming said heavy fractions and hydrogenating agent into a downwardly falling finely divided mixture, and means for introducing raw oil into said hydrogenator counter-current to and into contact with said mixture.

34. In an apparatus of the character described, an equilibrium chamber, a hydrogenator in open communication with said chamber, means for introducing a hydrogenating agent into said hydrogenator, means for supplying raw oil to said hydrogenator, means for repeatedly passing back 60 heavy fractions from said chamber through both said hydrogenator and said chamber, a separating hydrogenator and a vapor outlet from said chamber to said secondary hydrogenator.

35. In an apparatus of the character described, an equilibrium chamber, a hydrogenator in open communication with said chamber, means for introducing a hydrogenating agent into said hydrogenator, 70 means for supplying raw oil to said hydrogenator, means for repeatedly passing back heavy fractions from said chamber through both said hydrogenator and said chamber, a separating hydrogenator and a vapor outlet from said chamber to said secondary hydrogenator and means whereby said raw oil introduced into the hydrogenator is preheated by said separating hydrogenator.

36. In an apparatus of the character described, an equilibrium chamber, a hydrogenator in open communication with said chamber, means for introducing a hydrogenating agent into said hydrogenator, means for supplying raw oil to said hydrogenator, 80 means for repeatedly passing back heavy fractions from said chamber through both said hydrogenator and said chamber, a separating hydrogenator and a vapor outlet from said chamber to said secondary hydrogenator, 85 and a valved communication means connecting said hydrogenators, one end of said communication means being in a passage communicating with said equilibrium chamber.

In testimony whereof, I have hereunto set 105 my hand at Los Angeles, California, this 8th day of December, 1924.

MILON J. TRUMBLE.
